DESIGN FOR A CHAIR BACK

Joseph S. Opferman, Oakwood Heights, N. Y., assignor to Ganger, Inc., Manhattan, N. Y.

Application August 14, 1934, Serial No. 52,946

Term of patent 3½ years

To all whom it may concern:

Be it known that I, JOSEPH S. OPFERMAN, a citizen of the United States, residing at Oakwood Heights, in the county of Richmond and State of New York, have invented a new, original, and ornamental Design for Chair Backs, of which the following is a specification, reference being had to accompanying drawing forming part thereof.

Referring to the drawing:—

I claim:—

The ornamental design for a chair back as shown and described.

JOSEPH S. OPFERMAN,
